LAVATORY

Cecil W. Farrar, Buffalo, N. Y.

Application March 11, 1954, Serial No. 29,470

Term of patent 7 years

(Cl. D4—2)

To all whom it may concern:

Be it known that I, Cecil W. Farrar, have invented a new, original, and ornamental Design for a Lavatory, of which the following is a specification, reference being had to the accompanying drawing, forming a part hereof.

The figure is a perspective view of a lavatory embodying my new design.

The side opposite that shown is substantially like the one disclosed.

The bottom and the back or rear portion of the lavatory are plain.

I claim:

The ornamental design for a lavatory, as shown and described.
